TAPE COATING MECHANISM

Hubert J. Vachon, Haverhill, Mass., assignor to
 Boston Machine Works Company, Lynn, Mass.,
 a corporation of Massachusetts

Application August 20, 1947, Serial No. 769,745

1 Claim. (Cl. 91—33)

1

This invention relates to a mechanism for applying a coating of liquid adhesive material to one side of a tape.

In several industries, including the shoemaking industry, large quantities of reinforcing tape are used. For convenience in applying such tape, it is often coated with an adhesive material on its way to the applying mechanism. This can be conveniently done by passing the tape from the supply roll over a coating roll which picks up a film of adhesive material from a pool and carries the film to the tape which is run over the top of the roll and in contact therewith. The coated tape then goes to the applying machine either directly or after the coating has been dried to a tacky condition. In the applying machine, the tape is usually applied to a succession of objects such as shoe parts. When a work piece which has been taped is being removed from the machine and a fresh piece is inserted, there is usually a pause in the feed of the tape.

Furthermore, in the operation of the customary type of applying machine, longer pauses will occur, as when a case of taped pieces is removed from the vicinity of the machine or when a fresh supply of work pieces to be taped is brought up. When such pauses occur, the film of liquid adhesive material carried by the periphery of the coating wheel starts to drain back into the pool. Unless the pause is of very brief duration, the short portion of the tape which passes over the roll immediately after the resumption of feeding may receive an insufficient quantity of adhesive. According to the present invention, an auxiliary supply of adhesive material is maintained just beyond the coating roll, so that if there are any gaps or insufficiently coated areas on the face of the tape which has come into contact with the periphery of the roll, such areas will be adequately coated with material from the auxiliary supply. According to the invention, this auxiliary supply is maintained by surface tension between the under face of the tape itself and a scraper or wiper blade which makes an acute angle with the tape, converging to the tape in the direction of its motion. When the tape is being fed, it carries excess adhesive material from the roll to the wiper blade which removes the excess. This excess collects in the space between the blade and the tape and drips back into the pool, but enough adhesive is retained in that space by surface tension to take care of areas of the under surface of the tape which fail to pick up enough adhesive from the roll after a pause in operations.

2

For a more complete understanding of the invention, reference may be had to the following description of an embodiment thereof, and to the drawing, of which—

5 Figure 1 is a plan view of a mechanism embodying the invention;

Figure 2 is a section on line 2—2 of Figure 1;

Figure 3 is a section on line 3—3 of Figure 2;

Figure 4 is a section on line 4—4 of Figure 2;

Figure 5 is a section on line 5—5 of Figure 2;

Figure 6 is a sectional view of a tape and the liquid-applying elements acting thereon; and

Figure 7 is a perspective view of a short piece of folded tape to be coated by the mechanism.

As indicated in Figure 1, the mechanism may include a cylindrical container 10 adapted to hold an inverted bottle of liquid adhesive material, such as a suitable latex compound. The material escaping from the bottle flows into a rectangular box or receptacle 12 and forms a pool 14 therein, the box 12 being attached to and communicating with the container 10.

In the side walls of the box 10 are stub shafts 16 and 18 which support a coating roll 20 for free rotation on a horizontal axis. As indicated in Figure 3, the shafts 16 and 18 have conical ends projecting into suitable axial recesses in the roll 20 to support the same for rotation, but any other suitable support for the roll may be employed.

30 The shaft 16 is fixed but the shaft 18 is held in place by a set screw 22 which can be easily backed off to permit the removal of the roll 20 from the container 10.

35 The roll 20 dips into the pool 14, as indicated in Figure 2, the top of the roll projecting up through an opening 26 in a cover 30 on the box 12. The peripheral surface 31 of the roll is preferably knurled so as to pick up more effectively

40 a film of liquid from the pool. The tape to be coated passes from right to left over the box, as shown in Figure 2, passing first under a guide member 32, then over the top of the roll 20, then over a scraper or wiper blade 34, and finally under a guide member 36.

45 The machine illustrated in the drawing is particularly adapted to accommodate a longitudinally folded tape 40, such as is shown in Figure 7, but by reshaping the guide openings and the wiper 50 blade, any other kind of tape can be readily accommodated. The tape 40 is a special tape adapted for use in making an insole structure for a shoe. In making such a tape, a bias tape is coated on one face with a suitable adhesive material such as a latex compound which is allowed

to dry thereon to a tacky condition. The tape is longitudinally creased or folded so that the mid portion of the coated face comes together and sticks to form a central rib 42 between margins 44 and 46 on the uncoated face of the tape. For a certain type of insole structure, it is desirable to coat one side face of the rib 42 and the marginal area contiguous thereto. For this purpose, the tape is inverted to the position shown in Figure 7 and is fed through the mechanism illustrated in Figure 2 in that position. Thus, one side face of the rib 42 and the adjacent marginal portion 44 receives a coating of adhesive material from the roll 20.

To accommodate the extra thickness caused by the overlap of the rib 42 on the marginal portion 46, the guide bar 32 is notched, as at 50 (Fig. 3), to accommodate the folded tape 40, and a guide lip 51 projects out from the guide bar 32 (Figure 1) to bear on the single-ply portion of the tape so as to help to guide the tape through the notch 50. The guide bar 32 may conveniently be hinged, as at 52, to the cover 30 of the box, the free end of the bar being resiliently held down by a spring 54 on a screw 56 which projects up from the box cover 30 through to an aperture in the bar 32. The spring 54 permits the bar to yield upward whenever a thickened portion of the tape comes past, as, for example, the line of juncture between the successive lengths of tape which have been joined together to make a long tape to be rolled up into a sizable tape body.

The wiper blade 34 is similarly notched, as at 58, to accommodate extra thickness of the folded tape. The blade is inclined, as in Figure 2, so that when the tape extends thereover from the roll 20, as indicated in Figure 6, the blade makes an acute angle with the tape and converges therewith in the direction of motion of the tape.

In the space between the wiper blade and the under face of the tape, excess adhesive material, which has been picked up from the roll 20 by the tape, accumulates, as at 59, and a substantial quantity of it is held there by surface tension, the rest dripping back into the pool 14 through the opening 26. Thus, the wiper blade 34 serves a dual purpose of scraping or wiping excess adhesive material from the tape and also retaining an auxiliary supply 59 of adhesive material in contact with the tape so that in case any uncoated or inadequately coated areas of the tape come from the roll 20, such areas will thereupon receive a sufficient coating of adhesive material. This auxiliary supply thus becomes valuable when the mechanism illustrated in the drawing 55 is employed in conjunction with a tape-supplying machine to which the coated tape is fed from the coating mechanism so that the movement of the tape at the coating mechanism stops whenever the feed of the tape at the applying machine 60 stops.

Ordinarily, the operation of the tape-supplying machine is subject to frequent interruptions. During such pauses when the feed of the tape is halted, the film of adhesive liquid, which is in process of being raised from the pool 14 to the point of tangency with the tape at the top of the roll, starts to flow back into the pool so that when the feeding movement is resumed, the portion of the tape which touches the portion of the pe- 70

riphery of the roll from which the liquid adhesive is drained is liable to be insufficiently coated with the liquid. It is then that the auxiliary supply between the wiper blade and the tape serves to make up the deficiency and complete the coating of the under face of the tape.

The box cover 30 is removably mounted on the box and is held in place by a pin 60 at one end, which enters an internal lug 62 extending down from the cover, and by a screw 64, which engages a slotted lug 66 extending down from the other end of the cover, the screw 64 being threaded into a hole in the box wall. Adjustable spacing elements 68 and 70 are carried by the lug 66 and bear against the adjacent end wall of the box. Adjustment of the stops 68 and 70 serves to regulate the clearance between the edge 72 of the opening 26 and the periphery of the roll 20 (Figure 2). Thus, the depth of the film of liquid adhesive carried up from the pool 14 by the roll, can be regulated.

Secured to the under side of the box cover 30 is a rib 80 which surrounds the opening 26 so that if any of the liquid splashes on the sides of the opening, such liquid will not run along the under face of the cover but will drip back into the pool from the rib 80.

I claim:

30 A mechanism for coating tape, comprising a receptacle for liquid coating material, a cover member detachably and slidably mounted on said receptacle, said cover member having a rectangular opening therein and a rib on its under face extending around and adjacent to said opening, a roll rotatably mounted in said receptacle on a horizontal axis with the upper portion of its periphery projecting up through said opening, releasable means for securing said cover member on said box with an edge of the opening therein 35 adjustably spaced from the periphery of said roll, a guide bar mounted on said cover adjacent to said edge of the opening, said bar having a notch in its under face which has two portions of different depth to accommodate a longitudinally folded tape, a guide lip projecting horizontally from said bar over the portion of the slot which is of lesser depth, means yieldably pressing said bar down against the top of the cover member, a scraper blade mounted on said cover member over a portion of said opening remote from said guide bar, and a second guide bar mounted on said cover member and engageable by a tape after it has passed said scraper blade.
